UNITED STATES PATENT OFFICE.

VANDIVER TEAGUE, OF LENOIR, NORTH CAROLINA.

FLOUR-BOLT REEL.

SPECIFICATION forming part of Letters Patent No. 324,187, dated August 11, 1885.

Application filed May 28, 1885. (No model.)

To all whom it may concern:

Be it known that I, VANDIVER TEAGUE, a citizen of the United States, residing at Lenoir, in the county of Caldwell and State of North Carolina, have invented certain new and useful Improvements in Flour-Bolt Reels; and I do hereby declare that the following is a full, clear, and exact description of the same, reference being had to the annexed drawings, making a part of this specification, and to the letters and figures of reference marked thereon.

Figure 1 of the drawings is a side elevation of my improved flour-bolt reel. Figs. 2 and 3 are respectively the head and tail ends of the reel, and Fig. 4 a detail view on an enlarged scale, showing the means employed for tightening the bolting-cloth.

The present invention has relation to certain new and useful improvements in flour-bolt reels; and it consists in the details of construction and combination of parts, substantially as shown in the drawings, and herein-after described and claimed.

In the accompanying drawings, A represents the head of the reel, which supports one end of the usual longitudinal bars forming a part of the frame. These bars are formed of two sections, *a b*, between which are clamped and held the edges of the pieces of cloth forming the sections of the reel. The pieces of cloth near their outer edges are secured to strengthening-strips *c*, of wood or other material, and, if preferred, heavy cloth or canvas may be used, as found desirable. The sections *a b* of the bars are firmly held together by screws or other suitable fastenings, and their rear ends are rabbeted, as shown at *d*, to rest in slots *e* in the head A. The rabbeted ends of the bars

have secured thereto angle-plates B, one portion of each plate overlapping and coming flush against the head A, and has an elongated slot, *f*, through which passes a suitable clamping thumb-screw, *g*, which enters the head. The radial spokes *h*, extending from the usual shaft, C, pass up through holes *i* in the clamping-bars, and over each one of these holes *i* is secured a bushing, D, having a screw-threaded opening, which registers with the hole in the bar. A screw, E, passes through the screw-threaded hole in the bar, and the end thereof bears against the end of the spoke *h*. When the cloth on the reel or any section thereof becomes slack or sags, it may be quickly and conveniently tightened by first loosening the screw *g* and afterward screwing down the screws E, the latter acting as levers and the spokes *h* as fulcrums to force up the clamping-bars, and after the cloth has been sufficiently tightened the bars are held stationary by screwing up the thumb-screw *g* against the plate B.

Having now fully described my invention, what I claim as new, and desire to secure by Letters Patent, is—

A flour-bolt reel consisting of a central shaft 65 having radial spokes, longitudinal bars formed in sections, the bolting-cloth, bushings, and screws for tightening the cloth, slotted angle-plates, and thumb-screws for connecting the ends of the bars to the reel-head, substantially 70 as and for the purpose set forth.

In testimony that I claim the above I have hereunto subscribed my name in the presence of two witnesses.

VANDIVER TEAGUE.
